Primary Examiner — Jack Reickel

Assistant Examiner — Bobby W Jones, II

(57) **CLAIM**

The ornamental design for a water purifier with ice maker, as shown and described.

DESCRIPTION

1. Water purifier with ice maker

1.1 : Perspective

1.2 : Front

1.3 : Back

1.4 : Left

1.5 : Right

1.6 : Top

1.7 : Bottom

1.8 : Cross sectional

1.9 : Enlarged

The parts shown as solid lines in the present design are the parts intended for design registration as partial designs and the parts shown as dotted lines are intended not to be registered; reproduction 1.8 is a cross-sectional view configured along line B-B' of the front view, illustrating the outer shape excluding the internal shape; reproduction 1.9 is a partial enlarged view, enlarging A portion in the perspective view.

1 Claim, 9 Drawing Sheets
